(57) **CLAIM**

The ornamental design for an electronic vaporizer, as shown and described.

DESCRIPTION

FIG. 1 is a perspective front view of an electronic vaporizer. FIG. 2 is a front view of the electronic vaporizer of FIG. 1. FIG. 3 is a rear view of the electronic vaporizer of FIG. 1. FIG. 4 is a right side view of the electronic vaporizer of FIG. 1.

FIG. 5 is a left side view of the electronic vaporizer of FIG. 1.

FIG. 6 is a top view of the electronic vaporizer of FIG. 1. FIG. 7 is a bottom view of the electronic vaporizer of FIG. 1.

FIG. 8 is a front perspective view of the electronic vaporizer of FIG. 1, shown assembled with a pod.

FIG. 9 is a front exploded view of the electronic vaporizer and pod assembly of FIG. 8.

FIG. 10 is a rear perspective view of the electronic vaporizer and pod assembly of FIG. 8; and,

FIG. 11 is a rear exploded view of the electronic vaporizer and pod assembly of FIG. 8.

The broken lines consisting of equal length dash lines in the drawings depict parts of the electronic vaporizer that form no part of the claimed design. The broken lines consisting of long and short dashed lines in the drawings depict the boundary of the claimed invention and it is understood that the claim extends to the boundary, with the boundary forming no part of the claimed design.
